Primary Examiner — Ieisha N Price(57) **CLAIM**

The ornamental design for a clip for positioning gratings as shown and described.

DESCRIPTION

Clip for positioning gratings

- 1.1 : Back
- 1.2 : Perspective
- 1.3 : Top
- 1.4 : Left
- 1.5 : Right
- 1.6 : Bottom
- 1.7 : Front
- 2.1 : Back
- 2.2 : Perspective
- 2.3 : Top
- 2.4 : Left
- 2.5 : Right
- 2.6 : Bottom
- 2.7 : Front

The portions of the clip for positioning gratings shown in broken lines form no part of the claimed design.
